UNITED STATES PATENT OFFICE.

FRANK LOWELL BUTLER, OF CHICAGO, ILLINOIS.

ELECTRIC FIXTURE.

1,401,460.

Specification of Letters Patent. Patented Dec. 27, 1921.

Application filed October 2, 1920. Serial No. 414,211.

To all whom it may concern:

Be it known that I, FRANK LOWELL BUTLER, a citizen of the United States, and a resident of Chicago, in the county of Cook and State of Illinois, have invented a new and useful Improvement in Electric Fixtures, of which the following is a full, clear, and exact description.

My invention relates to improvements in electric fixtures, and it consists in the combinations, constructions, and arrangements herein described and claimed.

An object of my invention is to provide in an electric fixture an insulated stem adapted to insulate a lighting fixture or the like that depends therefrom from a fixed support without it being necessary to provide the usual insulating joint.

A further object of my invention is to provide a device of the type described that is at once simple in construction, ornamental in appearance, and effective for the purpose intended.

A further object of my invention is to provide a device of the type described that can be readily manufactured in large quantities at a relatively small cost, and which is thoroughly practical commercially.

Other objects and advantages will appear in the following specification, and the novel features of the invention will be particularly pointed out in the appended claims.

My invention is illustrated in the accompanying drawings, forming part of this application, in which—

Figure 1 is a central section through the device,

Fig. 2 is a plan view of a portion of the device,

Fig. 3 is a side view of the portion of the device shown in Fig. 2.

In carrying out my invention, I make use of a suitable fixed support, such as a gas pipe 1, that ordinarily depends from a ceiling 2. The pipe 1 is threaded exteriorly at its lower end and I screw thereon a coupling 3 that is interiorly threaded at each end and is provided with the usual partition 4 extending transversely across the bore of the coupling intermediate its length.

A tubular member 5 that is formed of a suitable insulating material, such as indurated fiber has its upper end threaded exteriorly for engagement with the interiorly

threaded lower portion of the coupling 3. The tubular insulating member 5 is also threaded adjacent its lower end to receive a nut 6 that supports a casing 7. The casing 7 tightly incases the tubular insulating member 5 for a portion of the length of the latter and serves a double function of preventing expansion of the tubular insulating member on account of inherent defects in the material or extraneous influences, such as temperature changes.

The nut 6 has a depending extension 8 formed with a central bore 9 and has its wall then fashioned into a link 10 to which suitable supporting members, such as the link 11, for supporting a lighting fixture 70 (not shown) may be secured.

The tubular insulating member 5 has an obliquely directed lateral aperture extending through its wall above the upper end of the casing 7 at a spaced distance below the lower end of the coupling 3. The upper and lower walls of the aperture 12 are beveled at 17 and 18, respectively. A plug 19 beveled at 19' that entirely fills the bore 14 of the tubular insulating member 5 is secured within the same with its beveled wall in alinement with the beveled upper wall of the aperture 12 as shown. Electrical conducting wires 13—13 from a lighting fixture or the like (not shown) passed into the bore 14 of the insulating member 5 through the bore 9 of the extension 8 are guided when moved upwardly through the aperture 12 and may then be connected to the wires (not shown) that ordinarily project 90 from the ceiling 2.

The usual canopy 15 is mounted on the casing 7 and secured in adjusted position therealong, as shown, by means of a set screw 16. The coupling 3 in the form of the device illustrated is hexagonal in shape, as best seen in Fig. 3 and therefore adapted to be engaged by an ordinary wrench or the like.

From the foregoing description of the various parts of the device, the operation thereof may be readily understood and requires no detailed description. The device is simple in construction and at the same time meets all the commercial requirements 100 for an electric fixture provided with an insulated stem, without it being necessary to provide the usual insulating joint. The tu-

tular insulating member is entirely concealed from view by the casing 7 and the canopy 15, wherefore the device may be ornamental in appearance or formed in any desired manner to match other fixtures, while being at the same time effective for the purpose intended.

One of the principal advantages obtained when the device is used in its preferred form 10 lies in the fact that the electrical conducting wires 13—13 can be passed from the bore of the stem through the aperture 12 without the difficulty that was usually encountered in accomplishing this result prior 15 to my invention.

I claim:

1. In an electric fixture, an insulated stem 20 consisting of a tubular insulating member threaded exteriorly at each end and formed with an obliquely directed lateral opening through its wall at a predetermined distance from the upper end thereof, a coupling screwing on the upper end of said insulating member and adapted for connection with 25 a fixed support, a casing arranged to cover the lower portion of said insulating member to a point adjacent the lateral opening, a nut screwing on the lower end of said tubular insulating member and formed to 30 provide a seat for said casing, said nut being formed with a depending extension having a central bore, said depending extension having a portion formed into a link adapted to support a lighting fixture element, electrical 35 conducting wires arranged to enter the bore of the tubular insulating member through the central bore in the depending extension to said nut and to pass therefrom through the obliquely directed lateral opening, and means disposed in the bore of the 40 insulating member above the obliquely di-

rected opening for diverting the electrical conducting wires through said opening.

2. In an electric fixture, an insulated stem 45 consisting of a tubular insulating member having a bore, said tubular insulating member being formed with an opening through its wall at a spaced distance from the upper end thereof, said opening having beveled upper and lower walls, means connecting 50 with the upper end of said insulating member for connecting the latter to a fixed support, means carried at the lower end of said insulating member for supporting a lighting fixture element, electrical conducting 55 wires for connection with the lighting fixture and arranged to enter the bore of the insulating member, and means for guiding the electrical conducting wires from the bore of the insulating member through the opening in its wall.

3. In an electric fixture, an insulated stem 60 comprising a tubular insulating member uniform in diameter for its entire length and having a lateral opening through its 65 wall, a plug inserted into the bore of said tubular insulating member at the upper end thereof and disposed within the bore in position to divert a flexible member from the bore of the tubular insulating member 70 through the lateral opening, said plug being formed with the lower end thereof beveled to extend from a lower horizontal plane to a plane located above the lateral opening, means connecting with said insulating 75 member at its upper end for securing the latter to a fixed support, and means connecting with the insulating member at its lower end for supporting a lighting fixture element.

FRANK LOWELL BUTLER.
